RADIOTELEPHONE EQUIPMENT

George G. Bradley, Great Neck, N. Y., assignor to
 Radio Corporation of America, a corporation of
 Delaware

Application July 26, 1946, Serial No. 686,265

17 Claims. (Cl. 250—6)

1

This invention relates to radio-telephone equipment.

It has particular application in two-way radio-telephone service where it is required to operate between ships and on ship-to-shore service. The invention is well adapted to the communication needs of ships which ply our inland water ways, such as rivers and lakes.

My invention is exemplified in certain radio-telephone equipment which has been built and successfully tested and which, as a specific embodiment, comprises transmitting circuits pre-tuned to as many as six radio frequency channels and six radio receivers, also pre-tuned.

The main body of the equipment, including the radio circuits, is usually located at some point remote from the operator's station. It is therefore required that it be completely operated by remote control. Preferably on ship-board two telephone stations are installed, one, say, in the pilot house, and the other in the radio operator's cabin or captain's quarters. The different transmitting circuits and receivers are adjusted for service on assigned carrier waves, such as have been provided by the Federal Communications Commission for use on the Mississippi River and its tributaries, or on the Great Lakes. The frequency range is within the limits of 2000 to 9000 kilocycles. The power output of the transmitter is preferably in the 75 watt range. The equipment has been proven satisfactory for service over distances as great as 800 miles. In placing and answering calls a frequency channel is usually chosen among six that are available whereby optimum conditions of communication may be chosen according to the time of day and with respect to the distance between stations.

Among the many noteworthy objects of my invention are the following, which are considered the more important:

1. To provide a flexibly operable two-way radio communication system especially adapted for use between ships and on ship-to-shore service on inland waterways, such as rivers and lakes.

2. To provide radio-telephone equipment the transmitter of which is serviceable with a minimum of delay for answering a call, and which will give satisfactory service over distances up to 800 miles.

3. To provide equipment for radio-telephone communication selectively on any one of a plurality of frequency channels certain of which would be allocated in the 4, 6 and/or 8 megacycle bands for daytime service, other channels being preferably allocated in the 2 to 3 megacycle band

2

for general service over land and fresh water; for example, between vessels which navigate the Mississippi River and its tributaries.

4. To provide radio-telephone equipment for use on ship-board whereby the placing of outgoing calls and the answering of incoming calls may be expeditiously handled at either of two stations, the main part of the installation being remotely situated.
5. To provide for continuous monitoring of incoming calls by means of a plurality of receivers, say six, which are operable in a stand-by condition; each receiver being tuned to a different frequency channel and their outputs being impressed upon a loud speaker or a selective call responsive device which responds to specific code signals and causes an alarm to be sounded upon reception of its code number.
6. To provide specialized switching devices in a multi-channel radio-telephone system whereby during a telephone conversation over a selected radio frequency channel all receivers are momentarily silenced while talking; all receivers of unused channels are completely silenced until the conversation is ended; and whereby the unused one of two telephone stations is rendered incapable of operation to in any way interfere with or intercept a communication carried on from the station momentarily in use.
- 30 My invention will now be described in more detail, reference being made to the accompanying drawings in which a single circuit diagram is shown by Figs. 1 and 2. Fig. 2 is to be placed on the right hand side of Fig. 1, so that the conductors which appear to run from one figure to the other may be placed in registry.

Referring first to Fig. 1, this figure in its entirety represents a control unit A for one telephone station. This control unit comprises a hook switch 101 whereon a hand-set 102 may be hung when not in use. The control unit also includes a loud speaker 103 which is principally used for continuous monitoring of incoming calls on the three medium or low frequency channels. A bell 104 is also provided in the control unit. As will be explained hereinafter, this bell is sounded by relay operation whenever a selective ringer 105 responds to code signals. This selective ringer is preferably connected through a ringer amplifier 50 106 to the output terminals of three receivers D, E and F which are tuned to the higher frequencies.

A channel selector switch having a multiplicity of ganged contact wipers and cooperating contacts wafers, lettered *a* to *j* inclusive, is provided

for use of the equipment on any of six radio frequency channels, numbered 1 to 6 inclusive. The gang switch also has a position "0" for stand-by operation, so that continuous monitoring of incoming calls may be had on any of the six receivers, three of which would impress their calls upon the loud speaker and the other three of which would be responsive by way of sounding the alarm through the selective ringer 105 and bell 104.

The control unit A shown in Fig. 1 may be the sole telephone station on board, but preferably two such units are provided. In Fig. 2, therefore I have shown as a block diagram a second control unit B the components of which will be understood to be exact duplicates of what is provided in control unit A.

The radio equipment is housed in a single cabinet which may be located wherever space can be conveniently found on shipboard. This cabinet contains the radio circuits of the transmitters and receivers, also certain switching devices which are remotely controlled from the control stations. Furthermore it houses the selective ringer 105 and a motor-generator for the transmitter power supply. The motor-generator is not shown, but it will be understood that it requires starting mechanism for which a control circuit 209 is provided. The receivers are operated from the ship's D. C. power line. The motor-generator is operated only when carrying on a conversation and provides anode, screen and negative biasing voltages for the transmitter tubes.

In order to provide for exclusive control of the equipment from either one of the two control units A and B, I provide certain relay equipment in a junction box. This relay equipment in combination with the switching devices of the control units is described and claimed in a co-pending application filed by myself jointly with Harry F. Mohr Ser. No. 679,344 on June 26, 1946. Other than terminals, the junction box contains only the relays 601, 602 and 604, the first two relays being parallel-connected.

The control unit

The remote control unit with which the hand-set 102 is associated is provided with a switch 107 having connections 81 and 82 to a similar switch at control unit B. Either of these switches may be used to connect or disconnect the ship's 115-volt D. C. power line +L to or from the telephone equipment. A pilot lamp 108 lights up when the ship's line is connected to the receivers. Switch 109A or 109B is used for selecting the particular control unit A or B respectively whereat a call is to be placed or answered. Assuming that the hand-set at control unit B has not been lifted switch 109A operates (before lifting the hand-set) to transfer telephone service from control unit B to control unit A. Switch 110 is provided for choosing between loud speaker and earphone reception. The hand-set 102 is provided with a push-button 111 which must be depressed when talking. In the hand-set is a ground connection common to the terminals of the earphone, the microphone and the push-button. The push-button circuit may be traced from ground through conductor 30, contacts of relay 602, the coil of relay 112 and thence to the negative terminal -C of the transmitter power supply, in which the +C is ground potential.

The relay 112 operates two movable contacts *b* and *e* which are associated with front contacts *a* and *d* respectively, and contact *e* normally rests

against back contact *f*. Several functions are performed as follows: (1) Closure of contacts *d* and *e* supplies negative line potential (-L) to the winding of relay 114 on the other side of which +L potential is supplied through normally closed contacts *b* and *c* of relay 113. Relay 114 operates, therefore, as a slave to relay 112. (2) The breaking of contacts *e* and *f* on relay 112 opens the cathode and gain control circuits of all the receivers, thus silencing the same. (3) Closure of contacts *a* and *b* on relay 112 in series with contacts *f* and *g* on relay 114 removes a blocking potential from the cathodes of the oscillator and the power amplifier tubes for keying the transmitter carrier on. This is accomplished by effectively short-circuiting resistor 122 (4700 ohms) through the very low value resistor 151 (5 ohms). Normally (with the push-button not depressed) the carrier wave is not propagated because of a positive potential applied to the cathodes just mentioned. This positive potential results from the voltage drop (approximately 100 volts) through resistor 122 which carries a bleeder current derived from a voltage divider (not shown but indicated by terminal T) connected across the anode potential source terminals in the motor generator, the negative terminal being grounded. Thus a potential drop exists in resistor 151 which is sufficient to energize the microphone.

Function (4) of the relay 112 is to open the circuit between the negative line terminal -L and all of the receiver gain control circuits, thus silencing the receivers while talking. This circuit when normally closed may be traced from relay contacts 112e-f through relay contacts 113f-e, through conductor 118, through branched rheostat elements 115, 116 and 117 to certain contacts of the channel selector which connect with gain control circuits 43, 44 and 45 leading to the cathodes of R. F. and I. F. amplifier stages (not shown) in the low frequency receivers A, B and C. The connections to corresponding cathodes in receivers D, E and F may also be traced from conductor 118 through other contacts of the channel selector and through conductors 40, 41 and 42 to the high frequency receivers.

Relay 114 when operated as a slave to relay 112 performs further functions thus:

(1) Closure of its contacts *a*-*b* connects the antenna 123 to conductor 124 which receives output signals from the transmitter 125 by way of one of the wafers in a motor-driven gang switch 126. This switch in its entirety serves to select the frequency of the carrier wave. Its novel features are described and claimed in my co-pending application Ser. No. 679,343 filed June 26, 1946.

Function (2) of relay 114 is to open the circuit at its contacts *c*-*b* so as to disconnect the antenna from conductor 127 having branches to each of the signal input terminals of the six receivers. During talking periods, therefore, no signal can reach the receivers. Function (3) is carried out by closure of contacts *d*-*e*, thus grounding the input circuits of the receivers for the purpose of noise suppression. Function (4) is fulfilled by closure of contacts 114f-g and is merely contributory to the performance (as above described) of function (3) of relay 112, that is, to close the microphone circuit. One virtue in the double make and break of this circuit is to minimize key clicks. The operation of relay 114 is delayed by a few micro-seconds with respect to that of relay 112.

The channel selector switch

Although this switch was briefly mentioned in the foregoing description its functions will now be more fully explained. Practical considerations, as well as the authorized assignments of radio frequency channels for Mississippi River shipping service dictated that the switch wipers be moved to positions 3, 4 or 5 for communication on the respective low frequency channels, and that positions 1, 2 and 6 be used when communicating on the relatively high frequency channels.

Position 0 is used for maintaining stand-by conditions in which the output circuits of the three low frequency receivers A, B and C are connected through conductor 39, switch wafer *h* and thence through contacts of the hook switch 101 to the loud speaker 103. Also the output circuits of the high frequency receivers D, E and F are connected through conductor 38 and switch wafer *i* and thence through conductor 37 to the ringer amplifier 106.

The gain control circuits for each of the receivers F, E, D, C, B and A is brought out individually through one of the conductors 40 to 45 inclusive and is connected to a wiper on one of the wafers *f*, *e*, *d*, *c*, *b* and *a* respectively.

A gang-controlled rheostat comprises adjustable resistors 115, 116 and 117 by which the volume of three receivers can be manually set. As shown in Fig. 1 resistor 115 at the left hand terminal is connected to different stationary contacts on wafers *f*, *c*, *b*, *a*, *e* and *d*. Resistor 116 is connected to one contact at the 0-position on wafer *c* and resistor 117 is connected only to the contact at the 0-position on wafer *b*. The right hand terminals of these three rheostat resistors are connected in common through conductor 118 to movable contact *e* on relay 113, thence through back contacts *f* of the two relays 113 and 112 and through movable contact 112—*e* to the —L terminal which supplies cathode potential to certain amplifier stages in all of the receivers. Preferably these are the radio frequency and the first intermediate frequency amplifier stages.

The gain control circuits for the high frequency receivers D, E and F are connectable directly to conductor 118 when the channel selector switch is set to any of the positions 0, 3, 4 or 5. Thus for stand-by conditions and when using any one of the low frequency channels for a communication the high frequency receivers are all operated at full gain.

In switch position 1 the gain control circuit for receiver D may be traced through conductor 42, wafer *d*, resistor 115, conductor 118 and thence through relay contacts to the —L terminal. Silencing of all the other receivers is then accomplished by opening their gain control circuits. So switch position 1 is useful for communicating on the channel to which receiver D is tuned.

In switch position 2 the gain control circuit for receiver E is connected through conductor 41, and wafer *e* to resistor 115 and is completed as described in the preceding paragraph. At the same time all other receivers are silenced. Likewise the gain control circuit for receiver F is connected through conductor 40 and wafer *f* to resistor 115 when switch position 6 is selected. All other gain control circuits are likewise open for that channel selection.

In switch positions 3, 4 and 5 the respective gain control circuits of receivers A, B and C are

singly connected in each case to rheostat 115 while the gain control circuits of receivers D, E and F are connected directly to conductor 118 and thence to the —L supply terminal. Hence, as previously mentioned, the high frequency receivers are operated at full gain and their output circuits are connected to the selective ringer for monitoring purposes during periods when any one of the low frequency channels is being separately monitored.

Switch wafer *g* has its stationary contacts 1 to 6 inclusive connected individually to pilot lamps 120 for clearly indicating the setting of the channel selector switch when it is moved away from the 0-position. The wiper on wafer *g* feeds current to a selected lamp from a 6-volt source upon closure of contacts *d* and *e* when the hand-set 102 is lifted from its hook 101.

Three of the pilot lamps 120 which stand in channel positions 1, 2 and 6 respectively are also connected through conductors 35, 34 and 33 respectively to contacts in the selective ringer unit 105. Unit 105 is arranged and adapted to close these circuits selectively when it is actuated by the proper sequence of audio frequency call signals. In practice the signal pulses are of 600 and 1500 cycle modulation which are alternated at a rate of 4 to 5½ cycles per second. The selector set on each ship may be arranged to respond to any one of a number of five-digit codes, so that the selective calling of any one of a group of stations operating on the same carrier frequency is possible. The terminating pulses of the call signal signify the communication channel to be used, and by illuminating a particular one of the pilot lamps 120 the answering party is enabled to turn his channel selector switch to the proper position for answering the call on any one of the high frequency channels.

Switch wafer *j* on the channel selector switch has connections through a cable 50 to individual contacts of a motor-driven rotary gang switch 126 at the main equipment unit. The details of construction and operation of switch 126 are not herein given since they are covered in my copending application Ser. No. 679,343 filed June 26, 1946. The setting of switch 126 is accomplished under control of a relay 113 which is in circuit with a selected conductor in cable 50 and operates to keep the armature of motor 128 energized until the setting of switch 126 corresponds with that of the wiper on wafer *j* of the channel selector switch. The gang switch 126 performs numerous functions, such as selecting the proper radio frequency tuning elements in the transmitting equipment and connecting the proper output circuit to conductor 124 for feeding outgoing signals to the antenna 123. The gear train through which the motor 128 drives the gang switch 126 includes preferably a worm reducing gear 129 and a Geneva movement 130.

In order to listen to a particular receiver the channel selector switch must be set to the desired channel. This connects the cathodes of the selected receiver to the volume control rheostat 115 and connects the output of this receiver to the loud speaker circuit. When one of the receivers A, B or C is selected the high frequency receivers D, E and F remain connected to the selective ringer, as hereinabove explained. And when one of the high frequency receivers is selected for a communication, then all of the non-selected receivers are silenced by opening their gain control circuits. This arrangement has been found

to meet the practical requirements of two-way radio telephone service in the Mississippi River and Great Lakes regions.

Transmitter circuits

The six sets of pretuned transmitter circuits are preferably of a type wherein carrier power in the 75-watt range is generated by a crystal controlled tuned anode circuit oscillator. A separate quartz crystal and oscillator anode tank circuit is provided for each transmitting channel. These circuits are switched by wafers on the gang switch 126.

By means of another wafer on the gang switch 126 the selected tuned transmitter unit is connected to a number of parallel-connected power amplifier stages. Audio frequency output from the modulator unit 121 is applied to the screen grids and anodes of those power amplifier stages. The modulated output is then coupled to one of six sets of antenna tuning circuits connections being made through still another wafer of the motor-driven gang switch. Finally, the antenna conductor 124 is connected to the selected antenna tuning circuit through one more wafer of the gang switch in unit 126. All these details of transmitter circuit switching may readily be worked out for different transmitter circuit designs by those skilled in the art. For purposes of this disclosure, therefore, it is preferred to symbolize by block diagram the transmitter circuits 125 and the gang switch 126 for channel frequency selection. It will be understood, however, that for the practical operation of my invention it is essential that the motor-driven gang switch 126 be capable of automatic adjustment to any position corresponding to positions 1 to 6 inclusive in the manually operable channel selector switch at the control unit. Furthermore, since the motor-driven switch 126 is capable of rotation in one direction from any previous setting to any desired new setting, it matters not where it is set at the time of shutting down the transmitter and of turning the manually operable switch to the stand-by position. In fact, the motor-driven gang switch has no stand-by position, for it needs none. But it always assumes a position corresponding to positions 1 to 6 inclusive of the manually operable gang switch, the latter exercising its control through its wafer *j*.

The earphone, microphone, modulator and push-button

The cord 131 for the hand set 102 contains 55 separate conductors for the microphone, the earphone and the push-button 111. Also for these three elements there is a common return conductor connected to ground.

When using the earphone the output from one of the receivers is brought through one or the other of the conductors 38-39 to the wiper on channel selector switch wafer *h* and thence through conductor 132, through closed contacts *b* and *a* of hook switch 101, and manual switch 119, this last being thrown to make connection with the earphone. The return circuit is through ground to a grounded terminal of the secondary winding (not shown) on the receiver output transformer. While listening the antenna 123 is 70 connected through normally closed contacts *b* and *c* of relay 114 to all of the receiver input terminals in parallel.

The microphone is connected through a circuit which may be traced from ground through

the microphone, thence through the modulator unit 121, and through a 5 ohm resistor 157 to ground. By closing contacts *f* and *g* of *b* and *a* of relay 112 a suitable voltage drop is produced through resistor 157 which constitutes the D. C. supply to the microphone, as heretofore indicated.

The push-button 111 is connected through conductor 38 to the winding of relay 112 and thence to the -C terminal of the transmitter power supply. The +C terminal is grounded. The transfer functions of relays 112 and 114 as controlled by the push button 111 have already been described. It should here be noted, however, that the receivers can all be silenced in two ways—one by operation of the push-button-controlled relay 112 which opens its contacts *e* and *f*; the other by operation of relay 113 which opens its contacts *e* and *f*. In the latter case the receivers are silenced during the movement of the channel selector switch 126 from one to another position. These four relay contacts just mentioned when normally closed complete the receiver gain control circuits to the -L power supply terminal, as hereinabove set forth.

25

The hook switch

When the hand-set 102 is lifted from its hook 101 contacts of the latter operate as follows: Contacts *b* and *c* open to silence the loud speaker. If loud speaker operation is preferred to earphone reception while engaged in a conversation, then switch 110 may be thrown to the proper position for that purpose. Closure of switch-hook contacts *a* and *b* connects the receiver output to the movable contact on switch 110.

Closure of switch-hook contacts *d* and *e* supplies potential from a +6-volt source terminal to the wiper on channel selector switch wafer *g* so as to light up one of the channel indicating pilot lamps 120. The negative terminal of this 6-volt source is the same as the -L terminal. So the return circuit common to all the lamps 120 joins that of the bell 104 and includes conductor 32, contact *f* on relay 602 which is directly connected to the -L terminal.

Closure of switch-hook contacts *f* and *g* connects conductors 9 and 36 to conductor 46, whereby +L potential is supplied (1) through switch wafer *j* and conductor 50 to relay 113 for operating the motor-driven channel selector switch 126; (2) through conductor 46 to terminal 209 on the starter coil of the motor-generator; and (3) through conductor 46 to the winding of a so-called "lock-out" relay 604 in the junction box. The function of this relay will presently be explained. The three branch circuits closed by switch-hook contacts *f* and *g* are all returned to the -L line terminal.

60

The junction box

The junction box contains terminal boards for the inter-connecting cables which are necessary for remote control of the radio equipment from either of two remote control stations. The junction box also contains the necessary relays 601, 602 and 604 for switching the control circuits from one remote control unit to the other.

As shown in Figure 2 the relays 601 and 602 have their windings connected in parallel and each relay operates nine movable contacts most of which engage with both front and back stationary contacts. Practically it is preferred to use three relays in place of relays 601 and 602 in order that the spring load of each relay coil

75

may not be excessive. The assignment of contact springs to the different circuits is immaterial aside from the fact that the front contacts, with one exception, must all lead to components in the control unit A shown in Figure 1 and the back contacts lead to corresponding components in the control unit B. To avoid unnecessary tracing of circuits the connections between the back contacts and control unit B have not been shown.

Normally control unit B is maintained in control of the system, relays 601, 602 and 603 being unenergized. Control may be switched to control unit A by momentarily closing switch 109A on that unit. This energizes relays 601 and 602, the circuit for which may be traced from the +L terminal at switch 107 in station A through one of the conductors 80 or 81, switch 107 at station B, conductor 9, switch 109A (momentarily closed), conductor 48, contacts c and b of relay 604, conductor 80 and through the coils of relays 601 and 602 to the -L terminal.

The relay circuit just traced is locked up by closure of contact e and its front contact on relay 602, this locking circuit extending temporarily (until the hand-set 102 is lifted from its hook) from live conductor 9 to conductor 79, thence through contacts of switch 109B, and conductor 80 to the coils of relays 601 and 602.

Now the exclusive use of control unit A for the period of a telephone conversation may be insured by lifting the hand-set thereat. This energizes the lock-out relay 604 in the following manner: Live conductor 9 connects through contact d of relay 602 to conductor 36, thence through contacts g and f of switch hook 101, conductor 46, contact c of relay 602 and the coil of relay 604 to the -L terminal. This circuit is also branched to the starter terminal 209 so that the motor generator may be started up for supplying power to the transmitter.

The lock-out function of relay 604 is effected this way: Closure of its contacts e and d makes direct connection between the +L terminal and conductor 9, and since relays 602 and 604 are both energized the +L potential traverses contact e of relay 602, conductor 79, contacts a and b of relay 604 and conductor 80 to the coils of relays 601 and 602. Note that contacts a and b of relay 604 are in shunt with switch 109B in control unit B, so that the opening of that switch cannot result in loss of control at the control unit A so long as its hook-switch is up. Furthermore, the switches 107 are effectively shunted by contacts d and e on relay 604, thus preventing the power from being shut off at the unused control unit.

When control unit B is to be used, the operator will first see that the power switch 107 is correctly set for lighting the "Power on" pilot lamp 108. If no sound is heard in his speaker he operates switch 109B momentarily in order to break the locking circuit that held relays 601 and 602 energized by previous use of control unit A. Control is then returned to control unit B, provided the operator at control unit A has hung up.

Now the lifting of the hand-set at control unit B results in energizing the lock-out relay 604 through circuits which are like those previously described in reference to control unit A, but which traverse the back contacts associated with movable contacts d and c on relay 602. Note that contact c of relay 604 is connected through conductor 48 to a contact of switch 109A at control

unit A. Therefore, the opening of contacts b and c on relay 604 establishes exclusive control at control unit B. Again, while relay 604 is energized the power switches 107 at the two control units are shorted by closure of contacts d and e on relay 604. So the two switches 107 and 109A at control unit A are both disabled during a telephone conversation carried on at control unit B.

Complete privacy of use of either control unit is insured by means of the transfer switch contacts of relays 601 and 602. Thus, considering relay 601 when it is not energized, the receiver output circuits 38 and 39 are carried to the manually operated channel selector switch 220 at control unit B. So, also with respect to the gain control circuits 40 to 45 inclusive. And conductor 37 which leads to the input terminal of the ringer amplifier is brought back from control unit B through the back contact nearest the core of relay 601.

Considering relay 602 when it is not energized, its back contacts which are associated with movable contacts a and d are connected to the microphone and push-button respectively on the hand-set 102B at control unit B. Back contacts associated with movable contacts b, c, and f lead exclusively to the hook switch and bell (not shown) at control unit B. Also the pilot lamps for channels 1, 2 and 6 at the control unit B are connected to the selective ringer 105 only when movable contacts g, h and i on relay 602 rest against their associated back contacts.

All of the conditions set forth in the two preceding paragraphs are modified by the energization of relays 601 and 602 so that complete privacy is obtained at control unit A whenever desired.

Operation

In the preferred embodiment of my invention the operating procedure for monitoring and answering calls is as follows:

(1) Turn the power switch 107 so that the pilot lamp 108 glows.

(2) Allow 15 seconds for receiver tubes to warm up.

(3) Turn the channel selector switch to "Stand-by," the 0-position. Adjust the receiver volume control clockwise as far as possible. Atmosphere noise and incoming calls on channels 3, 4 and 5 will be heard from the loud speaker. Incoming calls on channels 1, 2 and 6 will actuate the automatic ringer 105. When the bell 104 rings the incoming call will cause one of the pilot lights 120 to be illuminated corresponding to the channel number to be used in answering the call.

(4) If no sound is heard from the loud speaker, operate the control unit selector switch 109A or 109B momentarily and release. This shifts reception to the adjacent speaker.

(5) When the channel selector switch is on channel 3, 4 or 5 incoming calls on channels 1, 2 and 6 will still actuate the selective ringer.

(6) Listening on channels 1, 2 or 6 will disable the selective ringer.

(6) Remove the hand-set 102 from its hook and thereby cause the motor-generator to be started up. The motor-generator comes up to full speed in approximately three seconds. The warming-up period for the transmitter tubes is scarcely more than this, so that, for practical purposes the transmitter is ready to go on the air as soon as one has listened for a reasonable time to make sure of a clear channel.

Closure of switch-hook contacts *f* and *g* causes a restoring voltage to be applied to the stepping magnet (not shown) in the code selector, whereby the code wheel is restored to normal and the ringing of the bell 104 ceases.

(7) If it is desired to listen on a single channel to the exclusion of all others, the channel selector should be turned to the desired channel number and the volume control adjusted to a satisfactory level either for loud speaker use or ear-phone use.

The calling procedure is relatively simple:

(1) Turn the channel selector switch to the desired channel number and listen for one minute to make sure that the channel is not in use.

(2) Set the switch 110 to the desired position for use of either the loud speaker or the ear-phone.

(3) Remove the hand-set 102 from the hook 101 and wait for the channel pilot lamp to light up.

(4) To talk, hold down the push-button 111. Release to listen to the other party.

It is, of course, important to replace the handset on the hook after completing a call. The channel selector switch should also be turned to stand-by (0) position and the receiver volume adjusted to a sufficiently high level so that the next incoming call will be clearly heard on the loud speaker.

For service in the Mississippi River region the radio frequency channels at present assigned and their uses are as follows:

Channel.....	3	4	5	1	2	6
Frequency.....	2206	2738	2782	4162.5	6455	8840
To communicate with.....	New Orleans only	Ship to Ship		Various Shore Stations		
					Long Distance	
Coverage.....	Short Distance—Day-time Long Distance—Night				Day & Night	Day-time only

The frequency assignments as given in the above table are those now authorized for transmitting from Mississippi River ships. Reception is at the same frequencies except on channel 3, since New Orleans transmits at a frequency of 2598 kc.

For the Great Lakes region and for other radio-marine services the frequency allocations would be different, of course, so that no limitations are to be imposed upon the uses of my invention for transmission and reception of radio communications at any frequencies whatsoever.

It will be understood by those skilled in the art that various modifications of my invention may be made without departing from its patentable scope.

I claim:

1. In a selective switching arrangement for a radio-telephone installation, a multiple-position gang switch the wipers of which have selected positions each corresponding to a selected communication channel, a plurality of receiving units each having one amplifier stage and each differently tuned to one of the channel frequencies to be used, an audible responsive device, volume regulators, and gain control circuits one of each corresponding to one amplifier stage in each of said receiving units, said gang switch being connected to said amplifier stages, said response device, and said volume regulators and gain control circuits, said gang switch being operable: (1) to

connect a gain control circuit to the corresponding amplifier stage of the selected receiving unit through said volume regulator, (2) to connect the same selected receiving unit to said audible responsive device, and (3) to disconnect the gain control circuits from the remaining receiving units, thereby to silence the same.

5 2. In a selective switching arrangement for a radio-telephone installation, a multiple-position gang switch the wipers of which have a stand-by position and to any position corresponding to a selected communication channel, and, connected thereto, a plurality of receiving units each differently tuned to one of the channel frequencies to be used, a selective ringer responsive to code signals when received on certain of said channels, an audible responsive device, a volume regulator and gain control circuits individual to certain amplifier stages in each of said receiving units, said gang switch being operable in a stand-by position:

10 (1) to connect a number of said gain control circuits through said volume regulator to the corresponding amplifier stages, (2) to connect the corresponding receiving units to said audible responsive device, and (3) to connect the remaining receiver units at full gain to said selective ringer.

15 3. In a selective switching arrangement for a radio-telephone installation, a multiple-position gang switch the wipers of which have, selectively, a stand-by position and channel selecting positions corresponding to selected communication channels, and, connected thereto, a plurality of receiving units each differently tuned to one of

20 the channel frequencies to be used, a selective ringer responsive to code signals when received on certain of said channels, an audible responsive device, a volume regulator and gain control circuits individual to certain amplifier stages in each of said receiving units, said gang switch being operable in certain of its channel selecting positions: (1) to connect the gain control circuit to the selected receiving unit through said volume regulator; (2) to connect the same receiving unit to said audible responsive device; (3) to disconnect the gain control circuits of certain others of said receiving units, thereby to silence the same; and (4) to connect the remaining receiving units at full gain to said selective ringer.

25 4. In a selective switching arrangement for a radio-telephone installation, a multiple position gang switch the wipers of which have different selective positions corresponding to selected radio frequency channels, including certain channels in a high frequency band and other channels in a low frequency band, an audible responsive device, a selective ringer, a plurality of receivers, adjustable gain control circuits each corresponding to certain amplifier stages in each of said plurality of receivers, said receivers being individually tuned to different ones of said channels and thereby including low frequency and high frequency receivers each having output terminals and circuit means connected to the wipers and station-

ary contacts of said gang switch and also connected to: (a) said responsive device, (b) said ringer, (c) the adjustable portions of said gain control circuit arrangement, and (d) the output terminals of said receivers, said means being operable in accordance with the setting of said switch wipers: (1) to connect the output terminals of said low frequency receivers to said audible responsive device, (2) to connect the gain control circuit to the selected receiver, (3) to disconnect the gain control circuits from the remaining low frequency receivers, and (4) to connect the output terminals of said high frequency receivers to said selective ringer while maintaining the corresponding gain control circuits operable at full gain.

5. In a selective switching arrangement for a radio-telephone installation, a multiple position gang switch the wipers of which have different selective positions corresponding to selected radio frequency channels including certain channels in a high frequency band and other channels in a band of relatively low frequency, an audible responsive device, a selective ringer, adjustable gain control circuits individual to certain amplifier stages in each of a plurality of receivers, said receivers being individually tuned to different ones of said channels and thereby including low frequency and high frequency receivers each having output terminals, and circuit means connected to the wipers and stationary contacts of said gang switch and also connected to said responsive device, said ringer, the adjustable portions of said gain control circuits, and the output terminals of said receivers, said means being operable in accordance with the setting of the switch wipers: (1) to connect the output terminals of said high frequency receivers to said audible responsive device, (2) to connect the gain control circuit to the corresponding selected amplifier stage, and (3) to disconnect the gain control circuits from the remaining receivers, thereby to silence the same during a telephone conversation.

6. In a selective switching arrangement for a radio-telephone installation, a multiple position gang switch the wipers of which have selectively different positions corresponding to selected radio frequency channels including certain channels in a high frequency band and other channels in a band of relatively low frequency, and, connected to said switch, an audible responsive device, a selective ringer, adjustable gain control circuits individual to certain amplifier stages in each of a plurality of receivers, said receivers being individually tuned to different ones of said channels and thereby including low frequency and high frequency receivers each having output terminals, and circuit means connected to the wipers and stationary contacts of said gang switch and also connected to said responsive device, said ringer, the adjustable portions of said gain control circuits, and the output terminals of said receivers, said means being operable in accordance with the setting of the switch wipers to a "stand-by" position: (1) to connect the output terminals of said low frequency receivers in parallel to said audible responsive device; (2) to connect the gain control circuits of each of said low frequency receivers to the corresponding amplifier stage; (3) to connect the output terminals of said high frequency receivers in parallel to said ringer; and (4) to connect the gain control circuits of said high frequency receivers thereto at a full gain adjustment thereof.

7. In combination, a manually operable chan-

nel selector switch for use in a radio telephone system, said switch comprising a plurality of contact wafers each having a movable contact wiper and an associated array of stationary contacts, 5 all wipers being gang-controlled, and, connected to said switch, a plurality of receivers each tuned to a different carrier frequency and each having an output circuit and a gain control circuit, a manually operable volume regulator of the rheostat type, a listening device and a selective ringer unit, said switch being operable under stand-by conditions (1) to connect the output circuits of certain receivers to said listening device and simultaneously connect the corresponding gain control circuits to its receiver through said volume regulator, and (2) to simultaneously connect the output circuits of the remaining receivers to said selective ringer unit, with the gain control circuits for these remaining receivers being shunted across said volume regulator, and 10 said switch having other positions in which the output circuit of a selected receiver is connected to said listening device and the corresponding gain control circuit is connected to the selected receiver through said volume regulator.

8. The combination according to claim 7 in which said channel selector switch has selected positions in which it disconnects the gain control circuits of all receivers except a selected receiver while a selected receiver is connected its corresponding gain control circuit through said volume regulator to thereby silence all except the selected gain controlled receiver.

9. In a radio telephone system, a transmitter-receiver installation comprising pre-tuned radio frequency circuits for selective use on a plurality of different channels, two remote control units each comprising a hand-set, a channel selector switch to selectively choose one of said circuits when connected to said transmitter receiver, and remote control switching means, and a junction box containing relays connected to and subject to control from said remote control units, said remote control switching means being connected 35 to said circuits, said hand-set, and said channel selector switch and operable: (1) to connect the channel selector switch at a particular one of said control units to said transmitter receiver, and (2) to actuate at least two of the relays in 40 said junction box, thereby to cause the other control unit to be disconnected from the receiver.

10. In a radio telephone system, a transmitter-receiver installation comprising pre-tuned radio frequency circuits for selective use on a plurality of different channels, a motor-generator for energizing the circuits of the transmitter, a direct current source for energizing the receiver circuits and for driving said motor-generator, two remote control units each comprising a hand-set, a channel selector switch and remote control switching means, and a junction box containing relays subject to control from one of said control units whereat control is preempted, said remote control switching means being operable: (1) to connect the direct current source to said generator and to connect said direct current source to said receiver circuits, (2) to connect said pre-tuned circuits to the channel selector switch at the preempting control unit, and (3) to actuate at least two of the relays in said junction box, thereby to cause the unused control unit to be disconnected and disabled.

11. A two-way radio telephone system comprising multichannel transmitting and receiving apparatus including radio circuits having radio

frequency channels in one housing and two control units remotely situated with respect to each other and to said housing, audible responsive means at each of said control units and connected selectively one at a time to said receiving apparatus, a gang switch at each control unit and constituting means at times operable for selecting a desired radio frequency channel of two-way communication for use as a said transmitting and receiving apparatus, control unit disabling means, and relay means operable under control of switching devices at a pre-empting control unit to connect said disabling means to the other control unit thereby locking out and disabling the other control unit to prevent the same from exercising control and interfering with a telephone conversation which is commenced at said pre-empting control unit.

12. A system according to claim 11 and including means under control of said gang switch and operable by setting the same to a "stand-by" position to connect a plurality of said radio frequency channels to said receiving apparatus whereby a certain plurality of radio frequency channels are simultaneously monitored by said receiving apparatus and to connect the receiving apparatus to the audible responsive means whereby the audible responsive means receives the receiving apparatus output and is audibly responsive thereto.

13. A radio telephone system comprising a remote control unit and transmitting and receiving apparatus including components thereof which are pre-tuned for operation on different radio frequency channels, said apparatus being separately housed with respect to said remote control unit, a manually operable gang switch in said control unit, said switch having a "stand-by" position connecting a plurality of components simultaneously in circuit in said receiving apparatus for effecting multiple channel monitoring of incoming signals by said receiving apparatus, and having single channel selecting positions connecting selected components in circuit in said apparatus for obtaining single channel operation of the transmitting and receiving apparatus, a motor-driven gang switch in the housing of said transmitting and receiving apparatus, electrical means for causing the motor-driven gang switch to assume any one of a plurality of single channel positions corresponding to that to which the manually operable gang switch is concurrently set, said motor-driven gang switch constituting means connecting a single selected component in circuit in said transmitting apparatus for causing said transmitting apparatus to be tuned to a desired channel frequency corresponding to the selected receiver frequency, means connected to the manual gang switch and operable by selectively setting the manual gang switch to a single channel position for conditioning the receiving apparatus to translate incoming signals only as received on said desired channel frequency, and means controlled by the two gang switches for suppressing the operation of transmitting and receiving components which are tuned to non-selected channel frequencies.

14. A system in accordance with claim 13 and including an additional remote control unit similar to the first remote control unit and selective means for obtaining exclusive use of either of the two remote control units while locking out control of the transmitting and receiving apparatus by the non-selected remote control unit.

15. A radio telephone system comprising a re-

mote control unit and receiving apparatus including components thereof which are pre-tuned for operation on different radio frequency channels, said apparatus being separately housed with respect to said remote control unit, a manually operable gang switch in said control unit, said switch having a "stand-by" position to connect a plurality of components in said apparatus for effecting multiple channel monitoring of incoming signals by said receiving apparatus, and having other positions to connect a selected component in said apparatus to provide reception on a selected radio frequency channel, output circuits and gain control circuits for each of said differently tuned receiving apparatus components, said output and gain control circuits having connections completed by said manually operable gang switch in selected positions thereof whereby said apparatus effectively receives single channel voice reception and the concurrent reception of incoming selective code signals by others of said receiving apparatus components.

16. A radio telephone system comprising transmitting and receiving apparatus arranged for two-way service on any one of a plurality of radio frequency channels and having means for monitoring simultaneously a plurality of channels for incoming signals, a pair of remote control units each including a microphone-earphone hand-set, and control switches for establishing different circuit conditions in said system, a push-button on each hand-set, relay means subject to control by said push-button for conditioning said transmitting apparatus to radiate a signal modulated by a microphone of a selected hand-set, said relay means being at the same time effective for silencing the receiving apparatus, other relay means automatically operable to disconnect the other control unit until the hand-set which is in service is hung up, and channel selecting means operable at times to condition the transmitting and receiving apparatus for single channel two-way communication and at other times for multiple channel monitoring of incoming signals.

17. A system according to claim 16 and including a selective ringer and a loud speaker, circuits to connect certain channel-tuned units of said receiving apparatus and said loud speaker, other circuits to connect the ringer with the remaining units of said receiving apparatus, said channel selecting means being effective to make all of said circuit connections, and means for controlling the volume of response in the loud speaker.
